ORNAMENTING DEVICE AND METHOD OF MAKING THE SAME

Filed Sept. 6, 1929

Inventor
Alexander Weiner
by Horatio E. Bellone
Attorney

UNITED STATES PATENT OFFICE

ALEXANDER WEINER, OF PROVIDENCE, RHODE ISLAND

ORNAMENTING DEVICE AND METHOD OF MAKING THE SAME

Application filed September 6, 1929. Serial No. 390,665.

My invention relates to ornamenting devices adapted for use in the construction of jewelry and articles of personal adornment.

Features of my invention are the utilization of the heads or ornament carrying wires for securing the coherence of the constituent parts of the entire ornament, and the consequent avoidance of the use of solder or any independent binding members for this purpose.

Other features of invention are the adaptability of the ornament to interengagement with the end links of a chain or of chain sections, and the utilization of head carrying wires for the formation of the chain engaging members.

Invention resides in the above described structural features, and in the method of constructing the entire ornament.

20 In the accompanying drawings which form a part of this invention,

Figures 1 to 6 inclusive are front elevations of the elements of my ornament showing their successive positions in the formation of the complete ornamenting device, and

Figures 7 and 8 are front and side elevations respectively of the completed device.

Like reference characters indicate like 30 parts throughout the several views.

In constructing my device a plurality of similar structural units are employed. In Figure 1 three of these units are shown arranged in initial position comprising pliable or bendable metallic wires or rods a' , a^2 , and a^3 respectively; and ornamental heads, in this instance spherical in shape, b' , b^2 , and b^3 respectively, fixed to the wires.

With the three heads held between the 40 thumb and finger of one hand the three wires are grasped by the similar digits of the other hand and given approximately three turns forming three interengaging spirals c . The twisting operation draws the three heads 45 into the triangular relation shown in Figure 2, all the parts being disposed in a single vertical plane.

A fourth similar unit next has its head b^4 placed on top of the head b^3 while its wire 50 a^4 is turned approximately three times over

and around the other wires forming the coils d , as shown in Figure 3.

A fifth similar unit is next applied by resting its head b^5 on top of the head b^4 and turning its wire a^5 approximately three times under and over the prior wires, forming the coils e , as shown in Figure 4.

All the described assembled heads are in the same vertical plane. A similar unit is finally applied by placing its head b^6 in front 60 of the other heads and in contact with heads b' , b^3 , b^4 and b^5 , and winding its wire a^6 approximately four times over and around the preceding coils forming coils f , as shown in Figure 5.

The wires a' and a^2 are next laterally together bent away from the remaining wires, which are vertically pressed together, as shown in Figure 6, and with a pair of cutting pliers or other cutting implement the 70 wires a^3 , a^4 , a^5 , and a^6 are severed close to the coils f along the line $x-x$ of Figure 6.

The wires a' and a^2 are next severed intermediate their lengths along the line $y-y$ in the last mentioned figure. The truncated 75 portions of the latter wires are next bent up into vertical position, and with bending pliers the upper ends thereof are bent outwardly and downwardly in opposite directions to form attaching hooks j , as shown in the completed ornament illustrated in Figure 7.

While in the showing wires a' and a^2 are those selected for embodying the hooks j , it will be understood that any two of the group of wires a' , a^2 , and a^3 may be employed for 85 that purpose.

As shown in Figures 7 and 8 the six heads form a cluster K and the twisted and coiled head carrying wires form the stem L of the ornamenting device which carries the suspension hooks j .

I claim:—

1. In an ornamenting device, a plurality of ornamental heads, wires rigid with the heads, intermediate interengaging spirals in the wires, attaching hooks upon the upper ends of the wires, additional heads adjacent the first heads cooperating therewith to form a cluster, wires fixed to the additional heads, and loops upon the last mentioned wires em- 100

bracing the spirals of the first mentioned wires to form a stem above the cluster.

2. A method of forming an ornamenting device consisting in placing three units, each comprising pliable wires with terminal ornamental heads with the heads grouped in juxtaposition, twisting the wires into interengagement intermediate their lengths, applying to the engaged units a second group of similar units with their heads resting upon the first heads, and winding intermediate portions of the wires of the second group of units around the twisted portions of the first group of wires, next severing two of the three first mentioned wires intermediate their lengths, then severing all the remaining wires as they emerge from the wound portions of the wires, and finally bending two severed wires to form hooks.

20 In testimony whereof I have affixed my signature.

ALEXANDER WEINER.
